UNITED STATES PATENT OFFICE

ANTON YURKOVITCH, OF PITTSBURGH, PENNSYLVANIA

HINGE LOCK

Application filed February 18, 1931. Serial No. 516,623.

This invention relates to a hinge adapted for use with any suitable article such as a door, window or the like and more particularly to a hinge which can be locked in one or 5 more positions intermediate that of a fully closed or a fully opened position.

Known hinges of this type while mechanically satisfactory, are inconvenient and undesirable in that they require considerable 10 manual effort to adjust the article to which they are applied.

I have, therefore, invented a hinge construction which will obviate the above noted 15 defects and which will present additional advantages peculiar to its own construction.

An object of the invention is to so construct or modify a hinge that it may be easily and simply locked in one or more positions intermediate a fully closed or a fully opened 20 position.

Another object is to provide a hinge or so modify a known hinge that one or more slots are provided which extend across the joint of adjacent hinge barrels so that a locking member 25 may be applied thereto.

A further object is to provide a hinge with a special slot so that a locking or hand piece may be applied thereto to fix the hinge portions in predetermined angular relationship.

30 Other and further objects and advantages will be understood from the following description or will be appreciated by those skilled in this art.

In the accompanying drawing:

35 Figure 1 shows an elevational view of a hinge embodying the present invention;

Fig. 2 is a perspective rear view of the locking or hand piece which may be utilized 40 in connection with the invention of Fig. 1;

Fig. 3 is a bottom view of Fig. 2;

Fig. 4 is a fragmentary view similar to Fig. 1 of a modified form of the invention;

Fig. 5 is a fragmentary detail of the slot 45 arrangement of Fig. 4;

Fig. 6 is a view similar to Fig. 2 of a modified form of locking or hand piece used with the modification of Fig. 4; and

Fig. 7 is an enlarged section taken substantially along line VII—VII of Fig. 1.

Similar numerals refer to similar parts throughout the several views.

Referring first to the modification shown in Figs. 1, 2 and 3, I have represented a convenient form of the invention. In these 55 figures, 10 and 11 represent the ordinary leaves of a hinge having the usual apertures 12 for the purpose of fastening the hinge leaves by means of screws or the like (not shown) to the desired article or structural elements. In the usual manner also, the hinge leaves are provided with the registering hollow barrels 13, the hinge leaf 11 having three such spaced barrels for the reception therebetween of the two spaced barrels 60 of the hinge leaf 10. As is known in hinge construction, the barrels are registered and a pintle member inserted therethrough, said pintle having any desired enlarged head construction 14, there being, if so desired and 65 as is usual a similar construction at the bottom. Each of these enlarged heads 14 has an aperture 15 passing therethrough for the reception of a ring or other suitable member 70 75 16 to which may be connected a cord, chain or the like 17, as will be understood.

In carrying out my invention, I may, for example, cut a slot in adjoining barrels so that when the slots register the composite 80 slot extends across the abutting surfaces of such barrels. This slot is preferably longer and, if desired, wider as at 18 above the joint or abutting surfaces than below the same as at 19, so that the locking member 85 may be more readily inserted as will be appreciated. At the end of the cord or chain member 17 above mentioned, is connected the locking or hand piece 20 which conveniently 90 may be provided with a transverse hole 21 for the reception of a ring or other member 22, said cord or chain being connected to said ring, as shown in Fig. 1. The exact 95 appearance or contours of the hand or locking piece are relatively unimportant with the exception that such piece is provided on its rear otherwise flat surface with a projection, which, as shown in Figs. 2 and 3 consists of an upper plane portion 23 and a lower dovetailed portion 24. Each of these portions 100 extends approximately half the dis- 105

tance of the whole projection and the projection as a whole extends approximately about one-half the length of the rear face of the locking piece 20. The portions 23 and 24 are so dimensioned as to cooperate readily with and form a complement to the composite slot above mentioned with its portions 18 and 19 already described. The bottom portion 19 of said slot has dovetailed 10 walls complementary to said projection portion 24.

It is thus apparent that in order to lock the hinge leaves in predetermined position they are moved relatively to each other until 15 the nearest upper and lower slot portions register vertically, that is, become vertically aligned, whereupon the hand piece is placed so that the projection extends into the upper portion 18 of the slot whereupon it is moved 20 downwardly as far as it will go, thus locking all the members in the position indicated, simply and firmly, yet effectively.

In the modification shown in Figs. 4, 5 and 6, the upper portion of the slot is formed 25 T-shaped as at 25 and the material of the hinge barrel behind the portions between the lower edge of the cross bar of the T and the bottom of that hinge barrel is cut away or thinned as at 25'. This enables the arcuate extension 26 on plane projection 27 of locking piece 20' to be inserted in the T and then slid downwardly as will be understood to the upper edge of the subjacent hinge barrel where it, of course, stops. The arcuate 30 extension follows concentrically the curve of the hinge barrel and pintle so as to permit effective action without any binding of the parts. Otherwise the construction is the same and the operation and use are likewise 40 the same, except that as to the lower part 28 of the slot the walls are plane.

While they do not all show in the drawing there are a plurality of such registrable slot portions at various angles around the 45 circumference of the barrels so that the hinge leaves may be locked in any desired or required angular relationship. Some hinges work substantially around 360° of a circle and my invention is particularly applicable 50 to such hinges.

I am not limited to the type of hinge to which my invention can be applied nor am I limited to the usage to which the invention is put as any hinged members are suitable for 55 use of the invention where it may be desired to fix or stop the members in required or predetermined angular position. It is clear that the chain 17 may be connected to either head 14 and that when connected to the upper the 60 chain may hang down behind and be brought up from underneath when the locking piece is positioned.

It is clear that abutting hinge barrels may be provided in accordance with the present 65 invention with one or more notches which,

when aligned, are adapted to form a slot in which a projection complementary thereto may be placed for locking the hinge barrels in the relationship thereby set up. It is further clear that regardless of whether adjacent 70 hinge barrels have one or more notches that a slot is nevertheless provided at the desired location.

What I claim as new and desire to secure by Letters Patent is:

1. In a device of the character described, two superposed relatively movable abutting hinge barrels having notches alignable to 80 form a slot extending across the meeting surfaces thereof, and a member insertable into said slot for locking said hinge barrels in predetermined angular relation, said member including a hand piece with a projection thereon for reception in said slot.

2. In a device of the character described, two superposed relatively movable abutting hinge barrels having notches alignable to 85 form a slot extending across the meeting surfaces thereof, and a member insertable into said slot for locking said hinge barrels in predetermined angular relation, said member including a hand piece with a projection thereon for reception in said slot, said slot having a portion defined by dovetailed walls and said projection having a complementary portion 90 interfitting therewith.

3. In a device of the character described, two superposed relatively movable abutting hinge barrels having notches alignable to 95 form a slot extending across the meeting surfaces thereof, and a member insertable into said slot for locking said hinge barrels in predetermined angular relation, said member including a hand piece with a projection thereon for reception in said slot, said slot being 100 defined partially by plane walls and partially by dovetailed walls, and said projection being complementary thereto.

4. In a device of the character described, two superposed relatively movable abutting hinge barrels having notches alignable to 110 form a slot extending across the meeting surfaces thereof, and a member insertable into said slot for locking said hinge barrels in predetermined angular relation, said member including a hand piece with a projection thereon for reception in said slot, said slot being 115 substantially T-shaped and said projection being contoured to interfit therewith.

5. In a device of the character described, two superposed relatively movable abutting hinge barrels having notches alignable to 120 form a slot extending across the meeting surfaces thereof, and a member insertable into said slot for locking said hinge barrels in predetermined angular relation, said member including a hand piece with a projection thereon for reception in said slot, said slot having an enlarged upper portion and said 125

projection having an interfitting enlarged upper end.

6. In a device of the character described, two superposed relatively movable abutting hinge barrels having notches alignable to form a slot extending across the meeting surfaces thereof, and a member insertable into said slot for locking said hinge barrels in predetermined angular relation, said member including a hand piece with a projection thereon for reception in said slot, said slot having an enlarged upper portion and said projection having an arcuate enlarged upper end.

15 7. In a device of the character described, two superposed relatively movable abutting hinge barrels having notches alignable to form a slot extending across the meeting surfaces thereof, and a member insertable into said slot for locking said hinge barrels in predetermined angular relation, said member including a hand piece with a projection thereon for reception in said slot, said slot having an enlarged upper portion and the 25 material between said enlargement and the bottom of the barrel being cut away on the back thereof down to the bottom of the upper barrel, and said projection having an arcuate extension at its upper end receivable 30 in said slot and operable in said cut-away section.

8. In a device of the character described, two superposed relatively movable abutting hinge barrels having notches alignable to 35 form a slot extending across the meeting surfaces thereof, and a member insertable into said slot for locking said hinge barrels in predetermined angular relation, said member including a hand piece with a projection there- 40 on for reception in said slot, said slot having an enlarged upper portion and the material between said enlargement and the bottom of the barrel being cut away on the back thereof down to the bottom of the upper barrel, and 45 said projection having an arcuate extension at its upper end receivable in said slot and operable in said cut-away section, the engag- ing surfaces of both slot and projection being plane.

50 In testimony whereof, I have hereunto sub- scribed my name this 14th day of February, 1931.

ANTON YURKOVITCH.
